cago, Ill., a corporation of Illinois

Application September 9, 1929, Serial No. 391,130

81 Claims. (Cl. 82—2)

My invention relates generally to material working apparatus and more particularly to automatic lathes and machines of like nature.

One of the problems which confronts manufacturers at the present time is that of supplying machines which are capable of producing work at a speed which is commensurate with the demands in industry for more rapid production and for lower costs of manufacture. To meet this situation material working machines such as lathes, screw machines and the like have been provided. In many instances these machines have been designed to produce a particular type of work, and to design and build a special machine of this type requires the expenditure of considerable time and money. In many instances after the special machines have been completed, the part or work which was to be produced or machined thereby has been changed in form, thus rendering this specific machine obsolete and non-productive. Special machines require trained operators, and obviously in using such devices an unusually large number of different machines must necessarily be employed in a single plant which, of course, requires considerable non-productive supervision. The cost of maintaining such machines is comparatively high due to the time and effort spent in repairing and replacing specific parts thereof.

It is a primary object of my invention to provide a material working machine or apparatus which will avoid the above mentioned and numerous other disadvantages which have heretofore been experienced and to this end I propose to provide a fully automatic machine of simple, durable and economical construction.

More specifically it is an object of my invention to provide an automatic lathe of practical construction having comparatively few parts which may be efficiently operated with equal effectiveness by unskilled and skilled labor.

A still further object of my invention is to provide an automatic machine as above set forth which is equipped with a hydraulic control mechanism of improved and practical design, whereby the travel of the machine tools may be expeditiously controlled.

Another object of my invention is to provide a machine of the instant nature which is so designed that when the same is subjected to over-load conditions, the stopping thereof will be effected without the slightest possibility of breakage of any of the constituent cooperating parts.

Still another object of my present invention is to provide a fully automatic lathe which may

be controlled by the mere manipulation of a single control handle, the manual actuation of said handle serving to cause rotation of the supported work, the operative association of the tools with the work, the forward feeding of the tools, the withdrawal of the tools and the automatic return of the tools to their starting position.

In addition, I propose to provide a material working apparatus in which the speed with which the tools are moved, is automatically and hydraulically controlled in a unique and expeditious manner.

My invention further contemplates the provision of a hydraulic control mechanism in which a single automatic valve is employed to control all of the movements of the work supporting spindle and the tool supports or carriages, said single or unitary valve being also designed for manual as well as automatic manipulation.

The present invention also contemplates the provision of a lathe or machine of like nature having a plurality of cutting tools which are automatically reversible when they have reached the limit of their advancing movement, the reversing movement imparted to the tools being controlled by the tool which is last to complete its advancing or cutting stroke.

To attain these and other objects and advantages and in accordance with the general features of the invention, one embodiment of said invention includes a suitable rotary work supporting spindle having improved bearings for supporting the same in the head-stock. A front tool carriage is provided which is supported by a cylindrical bar, said bar being longitudinally movable for effecting travel of the carriage longitudinally of the work, and oscillatory for effecting movements of the tool toward and away from the work. A rear tool carriage is provided which is adapted to support a facing tool, said carriage being movable toward and away from the work. The machine spindle is rotatable in a counter-clockwise direction as viewed from the work supporting end thereof and a tail-stock is provided which is equipped with a hydraulically controlled and specially mounted centering element. A suitable unitary oil pump is employed to supply oil pressure for actuating the tool carriages and also for controlling a clutch mechanism on the main drive as well as the tail-stock center. By moving a single control lever which actuates a novel valve arrangement of unitary construction, the tool carriages in one illustrative cycle are rapidly moved into operative position, and at a predetermined stage said tools are moved at a

suitable feeding speed across the work surface. When said tools have reached the limit of their movement, a mechanism which is controlled by the tool carriage last to reach its limiting position, operates said valve mechanism to cause a rapid reversal of the carriages to their starting position. The arrangement of the machine is such as to enable the speed of travel of the tool carriages to be varied in accordance with the nature of the work. Suitable relief valves are provided which serve among other things to positively prevent damage which might otherwise result in the event that the machine becomes jammed, and by employing the above mentioned hydraulic control system, I am able to produce a very efficiently operable machine having an unusually small number of parts.

Having presented the foregoing general statement relating to the functional characteristics of a machine representing one embodiment of my invention, I will now proceed to describe said machine in connection with the accompanying drawings, wherein:

Figure 1 is a plan view of the machine, the tool carriages being shown in their initial positions, that is, the positions which they occupy prior to the advancement thereof toward the rotatably supported work;

Figure 2 is a front elevational view of the machine shown in Figure 1, the tool carriage in this figure being shown at the limit of its advanced position, as distinguished from the initial or starting position shown in Figure 1;

Figure 3 is a rear elevational view of the machine, disclosing the rear tool carriage at the limit of its advanced position, corresponding to the advanced position of the front carriage as shown in Figure 2;

Figure 4 is a vertical transverse sectional view taken substantially along the line 4-4 of Figure 2;

Figure 5 is an elevational view of a conventional oil pump mechanism which is detachably mounted at one end of the machine;

Figure 6 is a vertical sectional view taken longitudinally of the machine substantially along the line 6-6 of Figure 4;

Figure 7 is an enlarged fragmentary vertical sectional view taken along the line 7-7 of Figure 1, disclosing the arrangement of the single lever control device when the tool supporting carriages have reached the limit of their advancing movement and the lever occupies its neutral position;

Figure 8 is a plan view of the dog supporting slide and rack and pinion mechanism for operating same;

Figure 9 is an enlarged plan view of the oil control mechanism including the single lever mechanism, the main unitary control valve, and the distributor valve unit, said distributor and main valve units being shown in section for the purpose of more clearly illustrating the functional characteristics of these parts, all of said parts being shown in the position corresponding with the neutral position of the control lever shown in Figure 7 when the tool carriages have reached their advanced position;

Figure 10 is a vertical transverse sectional view of the oil control mechanisms taken substantially along the line 10-10 of Figure 9;

Figure 11 is an enlarged vertical sectional view taken transversely of the rear tool carriage, said section being taken substantially along the line 11-11 of Figure 4;

Figure 12 is a detailed elevational view of the

lever and link mechanism for controlling the oscillatory movement of the main oil control valve, said view being taken substantially along the line 12-12 of Figure 10;

Figure 13 is an enlarged central sectional view of one extremity of the main valve unit disclosing the advanced position of the valve within its casting;

Figure 14 is a transverse sectional view of the main valve structure taken substantially along the line 14-14 of Figure 13;

Figure 15 is a transverse sectional view taken substantially along the line 15-15 of Figure 13;

Figure 16 is a transverse sectional view similar to Figure 14 disclosing the valve after the same has been rotated to its pressure relieving position;

Figure 17 is an enlarged transverse sectional view of the distributor or orifice valve unit which is taken substantially along the line 17-17 of Figure 9;

Figure 18 is an enlarged plan sectional view of the main drive shaft and its associated driving elements;

Figure 19 is a detailed sectional view taken substantially along the line 19-19 of Figure 18;

Figure 20 is a fragmentary plan sectional view of the clutch operating device taken substantially along the line 20-20 of Figure 19;

Figure 21 is an enlarged fragmentary sectional view of the mechanism for controlling the supply of oil to the tail-stock piston, said view being taken substantially along the line 21-21 of Figure 1;

Figure 22 is a diagrammatic representation of the oil system and valve control mechanisms therefor, the main control valve being shown in its neutral position and the pistons corresponding to each actuated machine unit being shown in their starting position; and

Figures 23 to 26 inclusive disclosed the following positions of the single valve unit: Figure 23 rapid approach or traverse position, Figure 24 feeding position, Figure 25 rapid reverse position, and Figure 26 slow speed reverse position.

In order to clearly present the description of the machine disclosed in the foregoing figures, I propose to successively describe various units which constitute the machine structure.

Head-stock

The machine shown in the drawings comprises a head-stock which I have designated generally by the numeral 30 which includes a housing or frame 32 formed at the upper portion of a main frame 34. This main frame 34 rests upon a suitable base 36 as shown in Figures 1, 2 and 3. A spindle 38 is rotatably mounted at one extremity within an anti-friction bearing 40 and the opposite work supporting extremity of the spindle is mounted within a tapered bearing 42, Figure 6. The internal surface of this bearing 42 is tapered to receive a companion tapered surface of the spindle 38 and a set screw 44 is provided to secure said bearing against rotation within the housing 32. The outer extremity of the spindle is flanged to present a face-plate 46. The spindle is provided with an aperture having tapered walls 48 and a suitable adjusting nut 50 serves to adjustably position the bearing 42 with respect to the spindle. The anti-friction bearing 40 is provided with ball-bearings which are clamped together and placed under an initial load. These bearings are of such a construction as to allow both radial and thrust load and these bearings

are of the non-adjustable type. By having the anti-friction bearing and the bearing 42, the spindle 38 may be properly aligned between its forward and rear extremities. The spindle 38 carries a gear 52, Figures 6 and 18, which meshes with a driving pinion 54 connected through the medium of a pair of change gears 56 and 58 with the main drive-shaft 60. This main drive-shaft 60 forms a part of a driving mechanism later to be described.

Tail-stock

Supported upon the main frame 34 is a tail-stock which I have designated generally by the numeral 62, Figures 1 to 4 inclusive and Figure 6. This tail-stock 62 comprises a casing or body 64 and reciprocably mounted within said casing is a spindle or sleeve 66 which carries a center-piece 68. This center-piece 68 is mounted at both extremities within anti-friction bearings 70 and 72 which simulate the above mentioned spindle bearings 40. The inner end of the center member 68 supports a bearing block 74 and this bearing block 74 is adapted to be engaged centrally thereof by a ball 76 which is housed within a threaded plug 78. The bearings 70 and 72 serve to retain the center-piece 68 in perfect alignment and the ball 76 provides a very effective means in conjunction with the anti-friction bearings for taking up end thrust which might be occasioned when the center-piece is brought into operative association with the work. The threaded end of a piston rod 80 is mounted within the inner extremity of the sleeve 66 and the opposite extremity of said piston rod is connected with a piston proper 82 which is reciprocable within a cylinder 84. A threaded collar 86 and clamping ring 87 are positioned adjacent the outer end of the sleeve 66 and these parts serve to facilitate the mounting of the center-piece rotatably within the sleeve.

To effectively clamp the sleeve 66 in various positions of longitudinal adjustment, I provide an operating handle 88 which is pivoted at the rear side of the casing 64. As will be seen from Figure 3, the rear side of the casing 64 is split, and the rotation of the handle 88 from the position shown in Figure 1 to the position shown in Figures 2, 3 and 6 will serve to clamp the casing 64 against the sleeve 66. The movement of the handle 88 as described, serves not only to clamp the sleeve 66 in position but also operates a valve mechanism indicated generally by the numeral 90, Figures 6 and 21. This valve mechanism 90 forms a part of an oil system later to be described and includes a reciprocatory cylindrical valve 92 which is connected to the operating handle or lever 88 by means of a link 94. The valve 92 is reciprocable within a casing 96 and is provided with annular passages 98 and 100. The passage 98, when positioned as shown in Figure 21, establishes communication between cylinder ports 106 and 104, thereby permitting oil to be introduced within the cylinder 84 so as to effect the forward movement of the piston 82 to the left. Thus, when the handle 88 is moved in a counter-clockwise direction as viewed in Figure 1, the cylindrical valve 92 is moved so as to effect the automatic and hydraulic actuation of the center-piece 68, and during the final stage of the movement of the arm 88 the split casing is clamped against the sleeve 66. When the arm 88 is moved in a clock-wise direction so as to shift the valve to the left from the position shown in Figure 21, the valve 92 is moved so as to establish communi-

cation between ports 106 and 108. This causes pressure to be applied and thereby effect the movement of the center-piece to the right. Thus, in addition to unclamping the sleeve 66, movement of the operating handle causes the center-piece to be automatically moved out of engagement with the work supported thereby. The annular passage 100 in the valve 92 serves to establish communication between the ports 102 and 108 through a central valve passage 100a to permit the egress of oil from the advancing side of the piston 82 when oil is introduced through the ports 106 and 104. As clearly shown in Figure 22, the chamber adjacent the inner end of the valve 92 establishes communication between the ports 102 and 104 to effect the discharge of oil from the advancing end of the piston when the tail-stock center-piece 68 is being moved to the right.

In order to further facilitate the convenient manipulation of the tail-stock control handle 88, I have provided a ball-bearing mounting therefor as clearly shown in Figure 3. The handle rotates upon the upper threaded extremity of a vertical pin 107 which is secured in position against rotation and in proper vertical relation by a set screw 108. Thus, the longitudinal movement of the center-piece 68 is automatically controlled in response to the movement of the handle 88 and by having the above mentioned ball-bearing mounting, said handle may be moved with a minimum amount of exertion on the part of the operator.

Front carriage construction

From the foregoing it will be apparent that work may be conveniently associated with and removed from the main spindle and tail-stock center and I will now describe the structural characteristics of the front tool supporting carriage which I have designated generally by the numeral 110, Figures 2, 4 and 6. This carriage includes a base or frame 112 which is clamped upon and supported by a horizontally disposed cylindrical member or bar 114. The lower portion of the frame or base 112 is split to permit the same to be clamped in position upon the bar 114 by means of suitable bolts 116. This bar 114 is reciprocable and rotatable within bearings 118 and 120, said bearings being located in the main machine frame 34 as clearly shown in Figure 6. One extremity of the bar 114 is connected to a piston 122 which is reciprocable within a cylinder 124. It will be understood that said piston is moved to the left when oil is introduced in the right end of cylinder chamber and is moved to the right when oil is introduced in the left end thereof, Figure 6. The axial movement of the bar 114 serves to move the carriage 110 between the starting position shown in Figure 1 and the extreme advanced position shown in Figure 2.

The frame 112 extends forwardly of the machine as shown in Figures 2 and 4 and is supported by means of a screw 130, the lower extremity of which carries a roller 132. This roller 132 rests upon a guide bar 134 which is pivotally mounted at one extremity upon the main frame 34. The opposite extremity of the guide bar 134 is pivotally supported by a vertically disposed piston rod 136 and this piston rod is connected with a piston 138 which is vertically reciprocable within a cylinder 140. Mechanism later to be described is provided for controlling the introduction of oil within the chamber of the cylinder 140 to control the lifting of the piston 138. The

upward movement of the guide bar 134 is limited by an adjusting screw 142 carried by a bracket 144. A cross slide 146 is mounted upon the upper portion of the frame 112 and movement of the slide toward and away from the supported work is occasioned by means of a suitable screw 148 which makes a threaded engagement with the frame 112, Figure 4. The inner end of the slide 146 supports a suitable tool holder 150, said tool holder having suitable means for clamping a tool 152 in position thereon. It will be noted that the cutting end of the tool 152 is arranged to remove stock when the work is rotated in a clockwise direction as viewed in Figure 4. This direction of rotation is opposite to that experienced by work spindles in conventional types of machines.

The bar 114 and the guide bar 134 provide a very rigid support for the carriage 110 and it will be observed that any chips resulting from the engagement of the cutting tool 152 with the work will not come into contact with any of the carriage operating mechanisms. In other words, the guide bar 134 and its associated parts are completely shielded beneath the frame 112. The upward movement of the piston 138 causes the front carriage to be swung to the right, Figure 4, about the axis of the bar 114 so as to carry the tool 152 into operative engagement with the work, the limit of its swinging movement being determined by the position of the adjusting screw 142 against which the bar 134 is moved. This screw 142 may be adjusted so that when the carriage reaches the limit of its swinging movement, the tool 152 will be properly positioned for making a cut across the work surface. After the tool has been thus positioned, the bar 114 is automatically moved to the left by the actuation of means hereinafter to be described so that the tool 152 is moved longitudinally of the work from the position shown in Figure 1 to the position shown in Figures 2, 3 and 4. After the tool has reached the position shown in Figures 2 to 4 inclusive, the piston 138 is lowered to withdraw the tool from operative engagement with the work and the bar 114 is returned to its initial starting position.

In the drawings I have shown the bar 134 with its upper surface 154 positioned within a horizontal plane. However, the bar may be inclined when it is desired to cut a taper in the work. The surface 154 of the bar may be configured in various ways to enable the tool 152 to conform to variations in the peripheral contour of the work. Thus, it may be desirable in certain instances to provide the bar 134 with angularly disposed surface portions to bring about the desired cross feeding movement of the tool during the longitudinal travel thereof. The screw 148 provides a convenient means for making an accurate adjustment of the slide 146 along the frame 112 and a set screw 156 co-operates with clamp screws 158 in properly positioning the tool within the holder 150. The pistons 122 and 138 are operatively connected with an oil pump later to be referred to more in detail, which pump is driven from the same prime mover which actuates the drive shaft connected with the above described spindle.

Rear tool carriage

Attention is now directed to a rear tool carriage which I have indicated generally by the numeral 160, Figures 1, 3 and 4. This carriage includes a slide 162, Figures 4 and 11, which is slidably mounted upon a guide frame 164 carried by the main frame 34. This guide frame 164 is adjustably mounted upon the main frame and in-

cludes a cylinder 166 which houses a piston 168 connected to a piston rod 170. The outer extremity of the rod 170 is threaded and secured to the lower extremity of an arm 172 which depends from and is secured to the outer end of the slide 162. Thus, reciprocation of the piston 168 will cause reciprocation of the slide 162 toward and away from the work. A tool holder 174 is mounted upon the slide 162 and this tool holder accommodates a cutting tool 176 which is adapted to be clamped in position by means of suitable screws 178. By having the rear carriage mounted in the manner described, a very rigid support is provided for the tool 176.

As already stated, the rotation of the work as viewed in Figure 4, is clock-wise and hence the pressure exerted on the tool 176 during its operative engagement with the work is downward. This downward pressure is effectively counteracted by the rigidly mounted tool holder, slide, and frame. The tool 176 is employed for making a facing cut across the work as distinguished from the peripheral cutting action of the tool 152. The means for automatically controlling the movement of the piston 168 will be hereinafter described in connection with the description of the oil system. The underside of the slide 162 carries a rack bar 180 and this rack bar meshes with a gear 182, Figures 4 and 11, which is supported by the frame 164. Meshing with the gear 182 is a companion gear 184 which is keyed to a shaft 186. The outer extremity of the shaft 186 is rotatable within a bearing 188 which is formed integral with a housing 190, and secured to the shaft 186 within the housing is a gear 192. This gear 192 meshes with a rack bar 194 which extends at right angles with respect to the shaft 186. This rack bar 194 is pivotally connected at its opposite extremity with a slide 196, Figures 7, 8 and 9 which forms a part of the oil control mechanism about to be described.

Oil control mechanism

This oil control mechanism, Figures 9, 10, and Figures 22 to 26, inclusive, includes three co-operating units namely, a manual control mechanism indicated generally by the numeral 198, a main valve unit 200 and a distributor or orifice valve unit 202. These units operate to control the proper distribution of oil to various moving parts of the machine and in this connection attention is directed to the diagrammatic representation of the oil system shown in Figure 22. In this Figure 22 I have shown schematically an oil pump which is designated generally by the numeral 204. In Figure 5 I have shown an elevational view of this oil pump unit of standard construction. The oil pump per se does not form a part of the present invention except as it enters into combination with the oil system which is a part of this invention. Therefore I have refrained from disclosing in detail the structural characteristics of the oil pump 204 and it will suffice to say that this pump includes a rotary plunger pump unit 205, having the usual rotor 206 which is provided with a plurality of radially arranged pistons 208. This rotor 206 is adapted to be shifted within a housing 210 for the purpose of varying the displacement of oil. When the rotor 206 occupies a central position within the casing 210 no displacement of the oil will take place but when said rotor has been shifted to one side of the casing as for example by the manipulation of a handle 212, oil will be forced outwardly from a central pintle 214 through a pipe 216.

A low pressure gear pump indicated schematically in Figure 22 and designated generally by the numeral 218 pumps oil from a reservoir 220 and supplies oil at low pressure to the intake side of the rotary pump 205 through a pipe 222. At this point it should be noted that for the purpose of more clearly setting forth the oil system, I have indicated the high pressure pipe lines, that is, the pipe lines which carry oil from the high pressure side of the rotary pump 205 by means of heavy lines and the pipe lines connected with the low pressure gear pump 218 by means of light lines. The pipe 216 conducts oil from the rotary pump 205 into the main valve mechanism 200.

This main valve mechanism 200 includes a unitary valve 224 which is reciprocable and partially rotatable within a cylinder or casing 226 as clearly shown in Figure 9 and Figures 22 to 26 inclusive. It will be observed that the valve 224 is formed with a central bore or passage 228 and three annular peripheral passages 230, 232 and 234. The central passage or bore 228 communicates with a plurality of radially extending passages 236 which are positioned between the annular passages 230 and 232 and also communicates with radial passages 238 which are positioned between the annular passages 232 and 234. Passage 240 serves as a means of communication between the central passage 228 and a portion 242 of the chamber within the valve casing 226. The valve 224 is formed with a reduced section 244 which is reciprocable within a split bearing 246 and the extremity of this reduced section 244 is enlarged to provide a piston 248. The central bore or passage 228 extends through this reduced section 244 and into the piston 248, said piston being provided with a plurality of reduced passages 250, Figures 9, 13, 14 and 16, which are designed to permit oil to flow from the central passage 228 into a longitudinal passage 252 when the piston 248 occupies the position shown in Figures 13 and 14. The reason for this construction will be more apparent as the description progresses.

One extremity of the unitary valve 224 is connected to a rod 254 rotatable within a bracket which is pivotally connected to the free end of a lever 256. This lever 256 has a pivotal mounting 258 and is connected intermediate its ends to one extremity of a bar 260, the opposite extremity of said bar being pivotally connected to a shifter bar 262, Figures 9 and 10. This shifter bar 262 is reciprocable within spaced guides 264 and 266 which form a part of the manual control mechanism 198. The underside of the shifter bar 162 is formed with rack teeth 268, Figure 10, which mesh with a driving pinion 270 and the outer extremity of the bar 262 carries a vertically disposed pin 272 which is secured in position by means of a set screw 273. Reciprocation may be imparted to the shifter bar 262 by means of dogs 274 and 276 which are adjustably mounted upon the slide 196. The dog 276 is adapted to engage the pin 272 when the slide 196 is moved in response to the rearward travel of the slide 162 of the rear carriage 160. Likewise, when the slide 162 is moved forward, movement is imparted to the slide 196 so as to carry the dog 274 into operative association with the pin 272. The functioning of these dogs will be more apparent after the oil system has been described more in detail.

The manual control mechanism 198 which is also designed to impart reciprocating movement to the shifter bar 262 and consequently to the unitary valve 224, includes a manual control lever

278 which is carried by a shaft 280, Figure 10. The lower end of the handle 278 is formed with an arm 282 which is connected to one extremity of a link 284, the opposite end of said link being pivotally connected with one extremity of a valve 286 of the distributor valve unit 202. The shaft 280 carries the pinion 270 and therefore movement of the handle 278 will cause the bar 262 to be shifted. In the drawings I have disclosed the handle 278 in its neutral position and when the handle occupies this position oil, which is displaced by the rotary pump 205, circulates through the unitary valve mechanism 200 without causing any movement of the pistons included in the oil system. This will be more clearly understood when the oil system is described in detail.

The distributor valve mechanism 202 includes a housing 288, Figures 9, 10, 17 and 22. The main distributor valve 286 is reciprocable within the housing 288, and an annular passage 290 in said valve communicates with a pipe 292, which pipe is connected with the main control valve mechanism 200. Oil which passes through this pipe 292 enters the annular passage 290 and from this point may be distributed through ports 294, 296 and 298 (Figure 17), when the distributor valve 286 occupies the position shown in Figures 9, 10 and 22. Needle valves 300, 302 and 304 serve to control the passage of oil through these ports which thus form adjustable restricted orifices, and these valves are respectively connected with pipes 306, 308 and 310 as diagrammatically shown in Figure 22. Interposed between the pipe 310 and the needle valve 304 is a valve 312 which is operated in timed relation with respect to the movement of the slide 196 to open and close the oil circuit at this point. If the valve 286 is shifted to the left, Figure 10, in response to the swinging of the handle 278 to the right, the ports 294, 296 and 298 will be closed, thereby permitting unrestricted passage of oil from the annular passage 290 through by-passes 314 associated with each needle valve. In other words, by shifting the valve 286 to the left, Figure 10, (right in Fig. 20), increased displacement of the oil into the pipes 306, 308 and 310 may be obtained. These pipes are respectively connected with the vertical front carriage cylinder 140, the rear carriage cylinder 166 and the horizontal front carriage cylinder 124 as clearly shown in Figure 22.

Manual operation of oil system

Before describing in detail the manner in which the operation of my improved machine is automatically controlled, I will trace the various oil circuits disclosed in the diagrammatic representations in Figures 22 to 26 inclusive. In Figure 22 I have shown the main unitary control valve 224 in its neutral position. In this position oil is distributed from the gear pump 218 to the rotary pump 205 and then through the pipe 216 into an annular port 316 which at this stage communicates with the central bore or passage 228 through the radial ports 236. Oil from the passage 228 passes through the ports 240 and thence into the chamber section 242. This chamber 242 communicates with the low pressure gear pump 218 through a pipe 318. From the pipe 318 the oil is exhausted through the pressure maintaining and relief valve 460, together with the excess delivery of the gear pump 218.

Now assume that the operating handle 278, Figure 9, is moved to its extreme left position as shown by the dot and dash lines, which position

I will hereafter refer to as the rapid approach position. The shifting of this control lever causes the main valve 224 to be moved to the position shown in Figure 23. In this position oil from the pipe 216 passes through the annular passage 230 and thence through the pipe 292 which communicates with the distributor valve mechanism 202. It will also be noted that when the valve 224 occupies the position shown in Figure 23, the annular chamber 234 establishes communication between the central passage 228 of the valve and a low pressure pipe line 320 which is connected with a cylinder 322, Figure 22. The displacement of the oil through this pipe 320 causes a piston 324 in the cylinder 322 to be urged to the left, thereby rocking the rotor 206 to its extreme position of displacement within the casing 210. This is the position of maximum displacement and thus it will be clear that this increase in oil displacement will cause a corresponding increase in displacement of the oil introduced within the distributor valve mechanism 202. The annular passage 290 of the valve 286 will, at this period, have been moved so as to cut off the needle valve ports 294, 296 and 298, and oil will be conducted through the by-passes 314 Fig. 10 and through the pipes 306 and 308 which are connected respectively with the front carriage cylinder 140 and the rear carriage cylinder 166. The valve 312 will occupy a position shown by the dot and dash lines in Figure 22, thereby preventing oil from passing through the pipe 310 which is connected with the horizontal front carriage cylinder 124.

The introduction of oil within the cylinders 140 and 166 will cause a rapid swinging movement of the front carriage with its cutting tool 152 toward the work and the rapid sliding advancement of the rear carriage cutting tool 176 toward the work. This movement is what I have referred to as the rapid approach movement. As the piston 138 is moved upwardly, oil from the advancing side thereof passes through a pipe 326 and oil from the advancing end of the piston 168 passes through a pipe 328, said pipes having a common connection with a return pipe 330 which communicates with an annular port 332 provided in the casing 226. This port 332 communicates with the central passage 228 which, at this time, is connected to the low pressure side of the system through the pipe 318.

Assume now that the handle 278 is moved to its feed position as indicated on Figure 9. This will cause the valve 286 to be moved so as to close the non-adjustable ports or by-passes 314, Figure 10, and to establish communication between the annular passage 290 and the needle valve ports 294, 296 and 298. The main valve 224 will then be positioned as shown in Figure 24 and in this position the connection between the pipe 320 and the low pressure side of the system will be cut off, thereby permitting a spring 334 associated with the piston 324, Figure 22, to cause the retraction of said piston. Fluid from the pipe 320 and annular chamber 234 is then free to be displaced through a return pipe 323 to the reservoir 220. The retraction of said piston will cause the rotor 206 to be moved to its normal position of displacement within the casing 210. A normal feeding displacement of oil as determined by the setting of handle 212 will then pass through the pipes 216 and 292 and thence through the needle valves into the pipes 306, 308 and 310. At this time the valve 312 of the distributor mechanism will be positioned as shown by the solid lines in

Figure 22 so as to permit the passage of oil through the pipe 310 and this passage of oil will effect the movement of the horizontal front carriage piston 122 to the left. Movement of the piston 122 causes the front carriage to be fed longitudinally of the work at a feeding speed. At this period further upward movement of the piston 138 will be prevented by reason of the engagement of the guide bar 134 with the adjustable screw or stop 142, Figure 2. The rear carriage piston 168 will be moved forwardly at a feeding speed. As is obvious, the volume differential between the fluid displaced by the pump during feed, at the setting of the handle 212, and that transmitted through the needle valve orifices, is diverted through relief valve 458. As one carriage completes its feeding travel, and during the completion of the feeding movement of the other, the volume of diversion is of course increased. The handle 212 may be employed to control the pumping rate so as to avoid excessive diversion, which would tend toward excess heating of the fluid medium.

If, upon the completion of the forward stroke of the cutting tools, the control lever 278 is moved to its neutral vertical position, the main control valve 224 will occupy the position shown in Figure 9. As already described in connection with the starting or neutral position of the main control valve as shown in Figure 22, oil supplied through the pipe 216 will then pass through the radial ports 236, the central passage 228, the chamber 242 and thence into the return low pressure pipe 318. For the purpose of more clearly disclosing the automatic control features later to be described, I have shown the control mechanisms in this neutral position in Figures 7, 9 and 10, and obviously the various operating pistons will at this time be positioned at the limit of their advancing stroke in readiness to be reversed.

Assume now that the cutting tools have reached the limit of their advancing movement as above set forth and that the control lever 278 has been swung from the neutral position to the extreme position to the right, Figure 9, which I will hereinafter refer to as the rapid reverse position. When the lever occupies this position the main valve 224 will occupy the position shown in Figure 25. In this position the pipe 320 is again connected with the low pressure side of the system, thereby effecting the rocking of the rotor 206 to the left as above described. Oil which is thus displaced at an increased rate through the pipe 216, enters the annular passage 232 and then passes outwardly through the pipe 330 which communicates with the cylinders 124, 140 and 166 so as to cause the quick reverse movements of the pistons 122, 138 and 168. This serves to quickly carry the tools out of engagement with the work and also serves to effect rapid reverse travel of the piston 122 which is connected with the reciprocating bar 114 of the front carriage 110.

If it is desired to effect the reverse movement of the front carriage 110 longitudinally of the work and the rearward movement of the carriage slide 162 at feeding speeds, it is only necessary to move the handle 278 to the reverse feed position as indicated on Figure 9. This will cause the main control valve 224 to occupy the reverse feeding position shown in Figure 26. In this position the pipe 320 will be cut off from the low pressure side of the system, thereby automatically causing the rotor to assume the position of normal displacement and the oil will be dis-

placed through the pipes 216 and 330 at a normal feeding rate. When the tool carriages have been returned to their initial starting point, the lever 278 is moved to its neutral position, thereby moving the main control valve to the position shown in Figure 22.

It is also to be noted that the tail-stock control cylinder 84 is operatively associated with the low pressure side of the above described oil system through the agency of a pipe line 336, Figure 22, which is connected between the port 106 and an annular port 338 provided in the main valve casing 226. This annular port communicates with the low pressure side of the oil system through the radial ports 238 and the central passage 228 as clearly shown in the drawings. The port 102 of the tail-stock cylinder is connected by means of a suitable pipe line 340 to the reservoir 220.

Description of automatic oil control

Thus far the oil system has been described in connection with the manual manipulation of the control lever 278 and I will now proceed to describe the manner in which the actuation of the various moving elements of the machine are automatically controlled in accordance with one illustrative or selective cycle. For the purpose of obtaining a clear understanding of this mechanism, consider that the operating handle 278 occupies its neutral position and the pistons associated with the front and rear carriages occupy their starting positions as shown in Figure 22. After the work has been positioned between the work spindle and the tail-stock center, and the operator has properly adjusted the positions of the tools 152 and 176 with respect to the work, the operator moves the handle 278 to the rapid approach position, that is, to the extreme left, Figure 9. As already described, this causes a sudden upward movement of the front carriage piston 138 and a sudden forward movement of the rear carriage piston 168. The upward movement of the piston 138 causes the guide bar 134 and the roller resting thereon to be elevated, thereby causing the tool 152 to be carried into proper operative relation with respect to the work which, at this time, is rotating in a clockwise direction as above set forth. The limit of the upward movement of the bar 134 is determined by the position of the adjustable screw or stop 142.

As the rear carriage slide 162 is advanced in response to the movement of the piston 168, the meshing gears 182 and 184, Figures 4 and 11, are rotated, thereby causing rotation of the gear 192 carried by the shaft 186. This causes the rack bar 194 and the slide 196 connected therewith to be moved to the left, Figures 7 and 8. As the slide 196 is moved, the dog 272 is eventually carried into engagement with the pin 272 carried at the outer extremity of the slide bar 262. This causes the slide bar to be shifted to the right from its extreme left position, which position has hereinbefore been referred to as the rapid approach position of the lever 278. The shifting of the bar 262 causes the main control valve 224 to be shifted to the right, thereby causing the same to occupy the position shown in Figure 24. This position has been referred to as the feeding position, that is, the position which causes oil to be displaced from the rotary pump 205 at a normal feeding rate. It is also to be noted that during the forward movement of the slide 196, a dog 342 is carried into engagement with an arm

344 of a bell-crank 346, Figure 9, and this bell-crank is connected with the valve 312 of the distributor mechanism by means of a link 348. The engagement of the dog 342 with the bell-crank 344 causes the valve 312 to be moved to the position in Figure 9, thereby establishing communication between the pipe 310 and the needle valve port 288, Figure 17. This causes the horizontal front carriage piston 122 to be moved to the left, Figure 6, thereby imparting a feeding movement to the front tool carriage longitudinally of the work axis.

As the tool 176 reaches the limit of its forward movement, a lug 350, Figures 7 to 10 inclusive and Figure 12, is carried into engagement with a pin 352 which is carried by a housing 354 formed integral with the upper arm 356 of a lever mechanism 358. A coiled spring 360, Figure 12, is lodged within the housing 354 and counteracts the movement of the pin to the left in response to the engagement therewith of the lug 350. The outward displacement of the pin 352 is prevented by a collar 362. The lever mechanism 358 is formed with a depending arm 364 and the extremity of this arm is formed with an aperture 366 which receives a pin 368 carried by a slidable shaft 370. This shaft is slidably mounted in suitable brackets 372, Figures 7, 9 and 12, and a coiled spring 374 is interposed between one of the brackets 372 and a collar 376. This spring serves to constantly urge the shaft 370 to the left, Figures 7 and 12. The opposite extremity of the shaft 370 is pivotally connected to the outer end of an arm 378 carried at the upper extremity of a vertical shaft 380. The lower extremity of this shaft carries another arm 382 which is adapted to be engaged by a lug 384, Figures 7 and 9, which is carried by a ring 386 mounted upon the cylindrical front carriage bar 114.

When the bar 114 approaches the limit of its advancing movement, the lug 384 is carried into engagement with the arm 382 and this causes the shaft 370 to be moved to the right, Figures 8 and 12, against the action of the coiled spring 374. The movement of the arm 356 of the lever mechanism 358 to the left, Figure 12, in response to the engagement of the lug 350 with the pin 352 and the lug 384 with the arm 382 causes a link 388 to be moved to the left. The extremity of this link is provided with a slot 390 which receives a pin 392 carried by a valve oscillating guide 394, Figures 9, 12 and 13. This valve oscillating guide 394 extends within the casing 226 of the main valve unit 200 and is keyed to a reduced end section 396 formed integral with the valve 224 as by means of a radial lug 398. Movement of the link 388 to the left causes the valve oscillating guide 394 to be rotated in a clockwise direction to the position shown in Figure 12. In this position the reduced radial passages 250 of the valve piston 248, Figures 13 and 14, establish communication between the central bore or passage 228 and the passage 252. The passage 252 communicates with a section 400 of the valve chamber and thus oil introduced within this section 400 will cause an unbalancing of the main valve 224 so as to effect the movement thereof to the right, Figures 9 and 13. The valve 224 is thus carried to the reverse position shown in Figure 25 and as hereinbefore described, the valve in this position serves to effect the rapid reversal of the pistons associated with the front and rear tool carriages.

Referring again to the lever mechanism 358

and its associated parts, it should be understood that this mechanism in co-operation with the lug 350, carried by the slide 196 and the lug 384 on the ring 386, operates to prevent the reversal of the machine until all of the cutting tools have completed their advancing stroke. In other words, the reversing of the machine is controlled by the lug which is last to be carried into operative engagement with the lever mechanism 358. Consider for example that the front carriage tool 152 completes its cutting stroke after the rear carriage tool 176 has completed its stroke. In this case the lug 350 will engage the pin 352 before the lug 384 engages the arm 382, Figures 7 and 12. The engagement of the lug 350 with the pin 352 causes the arm 356 to be swung slightly counter-clockwise as seen in Fig. 12, the pin 368 normally being at the right end of slot 386. This carries the left surface of the aperture 366 into engagement with the pin 368 carried by the shaft 370. The spring 360 associated with the pin 368 is lighter than the spring 374 carried by the shaft 370 and hence further movement of the arm 356 counter-clockwise is prevented. The movement experienced by the link 388 in response to this initial swinging of the arm 356 causes rotation of the valve oscillating guide 394 but this rotation is not sufficient to condition the valve 224 for reversal. Subsequently the lug 384 is carried into engagement with the arm 382 upon the completion of the forward stroke of the cutting tool 152 and this causes the shaft 370 to be shifted to the right a sufficient distance to cause the lever mechanism 358 to be swung to the position shown in Figures 7, 9 and 12. The movement thus imparted to the link 388 is sufficient to complete the oscillation or rotary movement of the valve guide to the position shown in Figure 14. If the front carriage tool reaches the limit of its forward stroke ahead of the rear carriage, it will be apparent from the above explanation, that sufficient rotation will not be imparted to the main valve 224 until the lug 350 is moved into engagement with the resiliently mounted pin 352. In other words, by having sufficient play between the pin 368 and the wall of the aperture 366, a slight rotary movement is imparted to the valve 224 by the first lug to reach the limit of its advancing movement and final movement is imparted when the last lug completes its movement.

In Figure 13 I have disclosed an enlarged view of the piston end of the main valve and have shown the piston 248 in its advanced position. Immediately after the piston has reached this position, the pistons associated with the front and rear carriages experience a reverse movement and this carries the lugs 350 and 384 away from the pin 352 and the arm 382 respectively, thereby permitting the spring 374 to move the lever mechanism 358 so as to rotate the valve 224 from the position shown in Figure 14 to the pressure relieving position shown in Figure 16. The slot 390 provided in the link 388, delays the return of the valve 224 to its pressure relieving position shown in Figure 16, thereby insuring the complete forward stroke of the valve within its casing. When the valve 224 has been thus oscillated, communication between the central passage 228 and the passage 252 is interrupted, and communication is established between the passage 252 and an annular passage 402, Figures 9 and 16, so as to relieve the fluid pressure and bring the valve member into fluid pressure balance. This annular passage 402 communicates

with a pipe 404 which connects with the oil reservoir 220, Figure 22.

Drive mechanism

Various forms of driving mechanisms might be employed in connection with the above described machine and in the present embodiment I have disclosed a conventional prime mover in the form of an electric motor 406, Figures 1, 3 and 18, 10 which is adjustably mounted upon the machine bed 38 by means of screws 407. The drive shaft of this motor is connected to a driving sprocket 409 of the conventional oil pump unit 204 by means of a silent chain 408, Figs. 3 and 5, and is operatively connected with a sprocket 410 by means of a silent chain 412. The screws 407 serve to enable the motor to be adjusted with respect to the main drive shaft and oil pump. The sprocket 409 is laterally adjustable by means of a swinging bracket 411. The sprocket 410 is mounted upon the hub of a clutch element 414, which element is loosely mounted by means of ball bearings 416 upon the main drive-shaft 60. This drive-shaft 60 is supported at its outer extremity by means of a suitable ball bearing 418 and carries a pulley 420 which may be used for driving a cooling pump not shown. The clutch mechanism which I have designated generally by the numeral 422 may be of any practical design and in the present embodiment of the invention I have shown a clutch of the disc type. A clutch element 424 which is axially movable in response to the movement of actuating arms 426, Figure 18, serves to connect and disconnect the power supplied from the prime mover. The movement of these arms is occasioned in response to movement which is imparted to the collar 428 supported by members 430, Figure 19. These members 430 are connected to the outer extremities of spaced arms 432 which extend outwardly from and are formed integral with a vertical sleeve 434 mounted upon a shaft 436. The sleeve and shaft are supported by suitable brackets 438 which extend outwardly from a frame 440, Figures 1, 3 and 18, which is secured to the side of the head-stock frame 32. The change gear 58 is mounted at the outer end of the main drive shaft 60 and this meshes with the companion change gear 56 which in turn drives the pinion 54, said pinion meshing with the main spindle drive gear 52. From the foregoing it will be apparent that the clutch mechanism 422 serves to control the delivery of power from the prime mover to the work supporting spindle.

Hydraulic clutch control

I provide means for hydraulically and automatically controlling the actuation of the clutch mechanism 422 and this control means includes a cylinder 442 supported upon the frame 440, Figures 1, 19 and 20. A piston 444 connected to a piston rod 445 is reciprocable within the casing 442. Oil conducting pipes 446 and 448 are connected to opposite ends of the cylinder chamber and as clearly shown in Figure 22, the pipe 446 forms a branch of the high pressure pipe line 308 and the pipe 448 forms a continuation of the pipe 328 connected to the rear carriage cylinder 160. The outer extremity of the piston rod 445 is connected to the free end of an arm 450 mounted upon the upper end of the shaft 436 and it will thus be apparent that when oil is initially displaced through the pipe line 308 as above described, this displacement will cause the piston 444 to be urged to the left, Figure 20. This causes

the vertical shaft 486 to be rotated in a direction so as to carry the collar 428, Figure 18, into engagement with the arms 426 which in turn operate the clutch mechanism so as to positively connect the main drive shaft 66 with the source of power. This causes rotation of the work spindle 38. Thus, when the operator moves the operating handle 278 to the rapid approach or starting position as above described, the work spindle will automatically be connected to the source of power supply. When the flow of oil through the pipes 306 and 328 is reversed, a reversal of the flow of oil will also be experienced in the pipes 448 and 446 connected to the cylinder 442, thereby causing the piston 444 to be moved to the right, Figure 20. This effects the immediate disengagement of the clutch. In other words, when the tools have reached the limit of their operative stroke and the machine is thrown into reverse, the source of power supply is disconnected from the work supporting spindle. In some instances as for example during reverse feed it may be desirable to constantly maintain the driving connection between the source of power and the work spindle, and in such instances it is only necessary to tighten a set screw 452, Figure 20, and thereby secure the piston 444 in position at the left end of the cylinder.

Statement of operation

In operating the above described machine, the prime mover 406 is activated and this causes the conventional oil pump 204 including the rotary pump 205 and the gear pump 216 to operate. The single control lever 278 now occupies its neutral position so that oil is circulated through the main unitary control valve without causing any of the carriage operating pistons to be moved. The operator mounts the work upon the face plate 46 of the work spindle and by moving the tail-stock control lever 88 from the position shown in Figure 1 to the position shown in Figure 2, oil is introduced within the cylinder 84 so as to cause the center-piece 68 to be moved into association with the work and during the final movement of the handle 88, the sleeve 68 is clamped in position within the tail-stock casing 84. The front tool carriage 110 and the rear carriage 166 now occupy the positions shown in Figure 1. After the tools 152 and 178 have been properly positioned in their respective holders, in the described cycle of operation the operator moves the lever 278 to its extreme left position which has heretofore been referred to as the rapid approach position. This causes the main control valve 224 to be moved to the position shown in Figure 23 and the main distributor or orifice valve 286 is moved so as to close the adjustable or needle valve ports and establish communication between the oil supply pipe 292 and the pipes 306 and 308 through the non-adjustable ports or by-passes 314, Figure 10. With the valve 224 positioned as shown in Figure 23, the rotary oil pump 205 is conditioned for maximum displacement, thereby causing displacement of oil at a high rate through the pipes 306 and 308 which connect respectively with the front carriage cylinder 140 and the rear carriage cylinder 166. The piston 444 associated with the clutch mechanism is simultaneously actuated so as to establish driving connection between the work spindle and the prime mover. The upward movement of the front carriage piston 138 causes the guide bar 134 to be moved upwardly, thereby swinging the front carriage 110 so as to bring the tool 152 into operative associa-

tion with the rotating work. The forward movement of the piston 122 causes the rear carriage 166 to be rapidly moved forwardly so as to bring the tool 178 into operative association with the work.

At a predetermined time which is governed by the position of the dog 274 on the slide 196, the main valve 224 is automatically moved to the position shown in Figure 24 which has heretofore been referred to as the feeding position. In this position the oil pump 205 is conditioned for a feeding displacement of the oil and the distributor valve 286 is moved to a position whereby communication with the non-adjustable by-pass ports is interrupted and communication is established with the adjustable or needle valve ports. During the movement of the slide 196, the dog 342 engages the arm 344 of the bell-crank 346, Figure 9, and this conditions the valve 312 so as to establish communication between the needle valve 304 and the pipe 310 which connects with the front carriage cylinder 140. Thus, feeding movement longitudinally of the work is imparted to the front carriage in response to the movement of the piston 122 and feeding movement transversely of the work is imparted to the rear carriage tool.

When the cutting tools approach the limit of their feeding stroke, the lug 350 carried by the slide 196 approaches the pin 352 and the lug 384 carried by the ring 386 approaches the arm 382. The engagement of these lugs in the manner described causes the actuation of the lever mechanism 358 and this effects the oscillation of the main valve 224. This oscillation is effected in response to the tool which is last to complete its forward cutting stroke. The oscillation of the valve 224 causes the pressure at opposite ends thereof to become unbalanced and said valve is automatically and hydraulically moved from its feeding position shown in Figure 24, past the neutral position shown in Figure 9 and thence to its rapid reverse position shown in Figure 25. The oil pump is now conditioned for maximum displacement, thereby causing the tool carriage pistons and the clutch control piston to experience a sudden movement in the reverse direction.

As the tool carriages reach their initial or starting position, the dog 342 engages an arm 454 of the bell-crank 346 and this closes communication between the pipe line 310 and the main distributor valve 286. Contemporaneously with the completion of the rearward movement of the carriage 166, the lug 276 carried by the slide 196, Figure 9, is carried into engagement with the pin 272 carried by the slide bar 262 and this causes said bar to be moved to the left, thereby moving the valve 224 to its neutral position shown in Figure 22. By rotating the tail-stock handle 88 from the position shown in Figure 2 to the position shown in Figure 1, the valve 92 associated with the tail-stock is moved so as to effect the automatic retraction of the center-piece 68, thereby enabling the operator to remove the work supported by the spindle 38. The operator then inserts another article between the head-stock and tail-stock and moves the control lever 278 to its rapid approach position, thereby conditioning the machine to automatically perform a complete cycle of operation as above described.

Referring to Figure 22, it is to be noted that I provide the relief valves 458 and 460 in the high pressure and low pressure pipe lines. The valve 458 is connected with the high pressure pipe 216

and the valve 460 with the low pressure pipe 318. Thus, any undue pressures which might be built up in response to overload conditions to which the machine may be subjected, as for example jamming of certain of the parts, will not cause the machine elements to be subjected to excessive strains. This is due to the fact that any pressures built up in the system beyond a predetermined degree will cause the relief and safety valves 458 and 460 to open and permit the oil to be freely displaced into the reservoir 220. This safety feature is an important factor in connection with rendering my improved machine practically free from repairs and replacements which so often are necessary in automatic lathes and the like which are now in common use.

From the foregoing description it will be apparent that my improved automatic material working apparatus is of extremely simple yet durable construction and all the operating parts thereof are few in number as compared with conventional types of automatic turning machines. By rotating the work in a direction which is opposite to the usual direction of rotation, I have been able to design front and rear carriages which serve to rigidly support the cutting tools in position.

The unique arrangement of the single or unitary main control valve mechanism 204 enables complete automatic control of the machine, that is, complete control during the entire cycle of operation thereof without the necessity of using auxiliary control mechanisms. The oil pump mechanism 204 is detachably mounted in a convenient position upon the machine frame and may be bodily removed for purposes of repair or replacement with the same degree of ease with which a prime mover such as an electric motor might be removed. These conventional oil pumps may be kept in stock and be used for replacement purposes in the machine shop to meet any emergency. By providing the relief valves in the oil system as above described, the possibility of breakage in machine parts resulting from jamming or other overload conditions, is positively eliminated. This arrangement in a sense renders the device practically fool-proof in that a careless operator cannot in the least impair the operating effectiveness of the machine by causing the same to become jammed.

It will be apparent that the machine is adapted for manual as well as automatic control. To render the machine manually controllable it is only necessary to remove the pin 272 from the slide bar 262, thereby enabling all of the various movements of the tools to be manually controlled by manipulating the hand lever 278. In connection with the arrangement of the dogs positioned along the upper surface of the slide 196, it should be understood that this arrangement may be modified to suit the particular work for which the machine is to be used. That is to say, additional dogs may be provided for variously effecting the feeding and rapid traverse of the machine tools. It might be desirable in some instances to cause one or more of the tools to be fed at a feeding rate over a portion of the work and then at a rapid rate over another portion during the feeding stroke thereof. This can readily be accomplished by positioning additional dogs upon the slide 196. In other words, my invention is not limited to the particular arrangement of the dogs which have been disclosed but

is capable of many other modifications without departing from the spirit and scope thereof.

The simple arrangement of the pivoted guide bar 134 provides a very unique and simple device for controlling the position of the front carriage tool during its movement longitudinally of the work. In the drawings the guide bar 134 is shown in its simplest form, namely with a flat upper surface and the bar is shown in a horizontal position, whereby the tool is guided along a straight path from one end of the work to the other. However, this guide bar might be tilted so as to cause the tool to cut along a tapered surface or the surface contour of the guide bar may be varied so as to cause said tool to follow along an uneven surface contour in the work.

From the description given it will be seen that I provide a very simple and positive reversing mechanism which is automatically operable in response to the cutting tool which is last to reach the limit of its advancing stroke. In this way I am able to positively prevent any reversal in operation to take place until the cutting operations of all the tools have been completed.

By employing an oil system which includes high pressure and low pressure conditions, a flooded oil circuit is presented which renders possible smooth and positive actuation of the various movable parts. In this connection it should be understood that the rotary plunger pump displaces a definite amount of oil regardless of pressure conditions and it is this volume displacement as distinguished from pressure control which enables me to obtain very high running efficiency. The distributor valve unit enables the displacement of oil into the various pipe lines connected therewith to be adjustably controlled by the described needle valves, and the non-adjustable orifices or by-passes in said distributor valve unit provide an effective passage for the oil which is employed to effect rapid traverse in forward and reverse directions.

The manner in which I have rotatably mounted the tail-stock center within a reciprocable sleeve presents a very practical construction and the conveniently operable control handle enables the center to be reciprocated and locked in position with a minimum amount of effort and skill on the part of the operator. Various types of cutting tools may be employed for performing different cutting operations and it should be understood that my invention is not limited to the use of the particular types of tools shown in the drawings.

During the operation of a work spindle, heat is obviously generated to such an extent that the spindle will experience longitudinal expansion. By employing the described spindle and bearing construction, I am able to maintain a perfect oil film between the bearing and the tapered portion of the spindle at all times. This will be readily appreciated when it is understood that the spindle will expand longitudinally as the result of heat generated during the rotation thereof. The bearing with which the tapered portion of the spindle is mounted is housed within the head-stock frame and hence cannot expand outwardly. Therefore, the expansion of the tapered bearing will be inwardly. The inward expansion of the bearing surface will take up the space occasioned as the result of the longitudinal outward expansion of the spindle. In other words, when the tapered portion of the spindle is moved slightly outward, the bearing expands in such a manner as to conform to the

expansion of the spindle and thereby insure true running condition.

The anti-friction ball bearings employed at one extremity of the spindle are of the type which are placed under an initial load prior to the assembly thereof with the spindle. In other words, the ball bearings are contained within raceways and are continuously subjected to a load which is in excess of the load or thrust to which the spindle may be subjected. The tapered bearing at the opposite end of the spindle is constructed in such a way as to positively take up radial thrust loads to which the spindle is subjected under working conditions. Operators in changing work pieces within a rotary spindle often use the most convenient method to dislodge the work piece from the spindle and this method in many instances requires the use of a hammer or mallet. Obviously, by using a mallet the spindle is subjected to severe strains and unless a proper bearing is provided therefor, the alignment of said spindle will be disturbed. To meet these severe operating conditions I have arranged the tapered bearing so that the same may be axially adjusted without affecting the axial alignment of the spindle. The bearing 42 is properly machined to fit the spindle taper and the nut 50 enables said bearing to be conveniently adjusted so as to obtain proper oil space between the bearing and spindle at all times.

The bearings of the tail-stock center present a very practical and unusual construction. Certain conventional ball bearing constructions which are not placed under the above mentioned initial load, have a considerable amount of play which, of course, would prohibit their use in connection with a tail-stock center which must be accurately centered at all times. By having the tail-stock ball bearings placed under an initial load which is greater than the actual working load which would be imposed on the bearing, said bearing provides a very convenient and practical construction. The bearing 70 is designed to take up a very high percentage of thrust load in comparison with the radial load while the bearing 72 is designed to take up a high percentage of the radial load. The middle portion of the center-piece 68 is enlarged, thereby giving sufficient rigidity so as to positively prevent said center-piece from deflecting as a result of the load supported thereby.

It should also be borne in mind that one of the novel features of my distributor valve arrangement resides in providing egress ports which are of a proper restricted size. By having these ports of a predetermined restricted size, I am able to build up a pressure within the distributor valve which is in excess of that actually required in any of the individual pipe lines 306, 308 and 310. In other words, I am able to maintain uniform displacement of the fluid to all the carriage operating pistons regardless of the resistance to which the tools may be subjected. In connection with this question of uniform displacement it should be noted that in certain instances it might be advisable to employ a relief arrangement such as the relief valves 458 and 460 for relieving the high pressure fluid when utilized for rapid traverse purposes as well as during the feed in order to eliminate the possibility of unequal displacement to the cylinders during the rapid traverse cycle. This, however, is a matter of construction which is arranged in accordance with the work for which the machine is to be used.

Attention is also directed to the fact that the depending adjustable screw 180 which is secured to the underside of the front carriage enables the tool on said carriage to be adjusted toward and away from the work without varying the degree of overhang of said tool. That is to say, if it were necessary to move the tool with respect to its mounting toward the work, said tool would necessarily project beyond the inner surface of the carriage and hence the upward force to which the tool is subjected when cutting into the work, would not be counteracted with the same effectiveness by the horizontal bar 114. However, by having the tool projecting only slightly beyond the inner surface of the carriage, the upward pull or force is in a direction which is practically radial with respect to the bar 114. It should also be noted that the guide bar 134 may be adjusted so as to account for variation in size of the work piece. That is, in many instances castings or forgings must be turned which are provided with a certain amount of draft, thereby requiring a shallow cut at one end and a deeper cut at the other. This bar 134 may be adjustably positioned for the purpose of meeting such conditions. It is to be noted that the hydraulic mechanism for effecting reciprocation of the bar 114 is positioned axially with respect to said bar and this construction enables said bar to be oscillated without varying the position of the actuating means. In other words, during the oscillation of the bar, the piston 122 oscillates within its cylinder, which parts are co-axial with respect to the bar.

It is obvious that various changes may be made in the specific embodiment set forth for purposes of illustration without departing from the spirit of the invention. The invention is accordingly not to be limited to the precise embodiment shown and described, but only as indicated in the following claims.

Having thus described my invention, what I claim as new and desire to secure by Letters Patent is:

1. In a material working machine of the class described, a rotary work support, an oscillatory tool carriage for shifting a tool transversely of the support axis, a bar parallel with said support axis and providing a support for the carriage, and hydraulic mechanism for controlling the oscillation and speed of travel of said carriage, said hydraulic mechanism serving to propel the carriage in both of its directions of travel.

2. In a material working machine of the class described, a rotary work support, a tool carriage capable of oscillation transversely of the work support and reciprocable longitudinally thereof, a bar extending in parallelism with the support axis and providing a support for the carriage, hydraulic mechanism including a hydraulic actuator for controlling the oscillation of said carriage, means for reciprocating said carriage, and a shiftable control member for selectively controlling the speed of travel of said carriage during its reciprocation.

3. In a material working machine of the class described, a rotary work support, a tool carriage capable of oscillation transversely of the work support and reciprocable longitudinally thereof, a bar extending in parallelism with the support axis and providing a support for the carriage, hydraulic mechanism including a hydraulic actuator for controlling the oscillation of said carriage, means for reciprocating said carriage, a shiftable control member for selectively con-

trolling the speed of travel of said carriage during its reciprocation, and means for controlling the period of actuation of said hydraulic mechanism in timed relation with the operation of the reciprocating means.

4. In a material working machine of the class described, a rotary work support, a source of fluid power, a tool carriage swingable transversely and reciprocable longitudinally with respect to the rotary work support, a hydraulic mechanism for effecting the swinging of said carriage, and a valve mechanism shiftable in timed relation with the swinging of said carriage for controlling the actuation of the hydraulic mechanism, said valve mechanism being of unitary construction and shiftable in response to fluid power.

5. In a material working machine of the class described, a rotary work support, a tool carriage reciprocable transversely with respect to the rotary work support, hydraulic mechanism for effecting the reciprocation and controlling the speed of travel of said carriage, and valve means mechanically connectable with and thereby mechanically shiftable by power imparted from the movement of said tool carriage for controlling the actuation of said hydraulic mechanism.

6. In a material working machine of the class described, a rotary work support, a tool carriage swingable transversely and movable longitudinally with respect to the axis of said work support, a bar parallel with said support axis and providing a support for the carriage, hydraulic mechanism for effecting the transverse swinging movement of the carriage, hydraulic mechanism for effecting the longitudinal movement of said carriage, and control valve means for controlling the timed relation of operation of said hydraulic mechanisms.

7. In a material working machine of the class described, a rotary work support, a tool carriage movable transversely with respect to the rotary work support axis and movable longitudinally thereof, hydraulic mechanism for effecting transverse movement of said carriage, hydraulic mechanism for effecting the longitudinal movement of said carriage, a control valve including a cylindrical valve member longitudinally shiftable within a valve casing, said valve member being hydraulically shiftable in a given direction, and means operable in response to the longitudinal movement of said carriage for controlling the hydraulic shifting of said valve member.

8. In a material working machine of the class described, a rotary work support, a tool carriage capable of being oscillated transversely of the work support axis and reciprocable longitudinally thereof, a bar arranged in substantial parallelism with the support axis and providing a support for the carriage, hydraulic mechanism for controlling the oscillation of said carriage, hydraulic mechanism for effecting the longitudinal movement of said carriage, a second tool carriage disposed oppositely with respect to the first mentioned carriage and reciprocable transversely of the work support axis, hydraulic mechanism for effecting transverse movement of said last mentioned tool carriage, and control valve means for controlling the timed relation of operation of said hydraulic mechanisms.

9. In a material working machine of the class described, a rotary work support, a tool carriage movable transversely with respect to the rotary work support axis and movable longitudinally thereof, hydraulic mechanism for effecting transverse movement of said carriage, hydraulic

mechanism for effecting the longitudinal movement of said carriage, a tool carriage oppositely disposed with respect to the first mentioned carriage and movable transversely with respect to the work support axis, hydraulic mechanism for effecting the transverse movement of said last mentioned carriage, a valve mechanism, and means operable in response to the movement of said carriages for establishing mechanical connection between said valve and one of said carriages to thereby control the actuation of the hydraulic mechanism associated therewith.

10. In a material working machine of the class described, a rotary work support, a tool carriage movable axially and transversely with respect to the axis of the rotary work support, and a vertically shiftable hydraulic actuator providing the sole means for controlling the complete reciprocation of said tool carriage, and for maintaining said carriage in a preselected position during its axial movement, said actuator being continuously in operative association with said carriage structure for moving said carriage toward a supported work piece.

11. In a material working machine of the class described, a rotary work support, an oscillatory and longitudinally shiftable tool carriage, an oscillatory guide member for effecting the oscillatory movement of said carriage, means for effecting movement of the carriage longitudinally of the support axis, said guide member being maintained in operative association with said carriage during the longitudinal movement of the carriage, and means for actuating said oscillatory guide member.

12. In a material working machine of the class described, a rotary work support, a tool carriage capable of being oscillated transversely toward and away from the axis of said work support and movable axially thereof, a pivotally mounted guide member engaging said tool carriage, means for moving the tool carriage longitudinally of the support axis, and means for moving said guide member about its pivotal point to effect movement of the tool carriage toward the work, and for maintaining predetermined transverse positioning of the carriage during its axial movement.

13. In a material working machine of the class described, a rotary work support, an oscillatory carriage movable toward and away from the work axis and longitudinally thereof, a pivoted guide bar providing a rest for said carriage, means for pivotally moving said guide bar to effect movement of the carriage toward the work, means for moving the carriage longitudinally of the support axis, and means for adjustably limiting the movement of said pivoted guide member.

14. In a material working machine of the class described, a rotary work support, a tool carriage movable longitudinally of the support axis and capable of being oscillated toward and away from the work, an oscillatory guide member for supporting said carriage, mechanism for effecting movement of the carriage longitudinally of the support axis, a hydraulic mechanism for oscillating said guide member to effect the oscillation of said tool carriage, and control means for controlling the timed relation of operation between the longitudinal and oscillatory carriage actuating mechanisms.

15. In a material working machine of the class described, a rotary work support, a tool carriage capable of being oscillated transversely with respect to the work supporting axis and movable

longitudinally thereof, a pivotal support for said carriage, said carriage having a laterally extending portion, a follower member supported beneath said laterally extending portion, and an oscillatory guide bar providing a rest for said follower member, means for effecting movement of the tool carriage longitudinally of the support axis, means for oscillating said bar to effect movement of the tool carriage toward the work, and control means for controlling the timed relation of operation between the longitudinal and oscillatory carriage actuating means.

16. In a material working machine of the class described, a rotary support, a horizontally disposed oscillatory support bar capable of being moved longitudinally, a tool carriage mounted upon said bar, mechanism for oscillating said bar to move the tool carriage transversely with respect to the work support axis, hydraulic mechanism connected to said bar for effecting longitudinal movement thereof, and control means for controlling the timed relation of operation between the longitudinal and oscillatory bar actuating mechanisms.

17. In a material working machine of the class described, a rotary work support, a horizontally disposed oscillatory support bar which is longitudinally movable, a tool carriage mounted on said bar, hydraulic mechanism for effecting the oscillation of said bar to move the tool carriage toward the work, hydraulic mechanism for effecting longitudinal movement of said bar to cause the tool carriage to travel longitudinally of the work axis, and control valve means for controlling the timed relation of operation of said hydraulic mechanisms.

18. In a material working machine of the class described, a rotary work supporting spindle, a front tool supporting carriage movable with respect to work carried by the spindle, a rear tool supporting carriage movable with respect to said work, a substantially horizontal bar for pivotally supporting one of said carriages, and means for rotating the spindle in a direction so as to apply pressure upwardly against the tool supported by the pivotally supported carriage and downwardly on the tool supported by the other carriage.

19. In a material working machine of the class described, a rotary work supporting spindle, a tool carriage disposed on one side of the spindle axis and capable of being oscillated toward and away from the work, and a reciprocably slidable tool carriage disposed on the opposite side of said spindle axis, said reciprocable carriage being capable of movement toward and away from the work, said axis of oscillation being positioned below the tool supporting section of said first named carriage so as to counteract the tendency for said carriage to experience a swinging movement during the cutting operation of a work piece supported by the spindle.

20. In a material working machine of the class described, a rotary work supporting spindle, a tool carriage disposed on one side of the spindle axis and capable of being oscillated toward and away from the work, a reciprocable tool carriage disposed on the opposite side of said spindle, said reciprocable carriage being capable of movement toward and away from the work, and means for effecting rotation of the work spindle in such a direction as to apply pressure upwardly against the tool supported by the oscillatory carriage and downwardly against the tool supported by the reciprocable carriage.

21. In a material working machine of the class

described, a rotary work support, a plurality of tool supporting carriages, said carriages being movable for bringing tools supported thereby into operative association with the work, a fluid operated actuating mechanism associated with each carriage, a fluid control mechanism for governing the operation of said carriage actuating mechanisms, said control mechanism including a unitary valve construction comprising a valve member longitudinally shiftable within a casing, said valve member being shiftable hydraulically in at least one direction, said valve member being normally maintained hydraulically in balance in a plurality of shifted positions, means for supplying fluid thereto, and fluid conducting means connecting said unitary valve mechanism with the carriage actuating mechanisms.

22. A material working machine of the class described including a rotary work support, a plurality of tool supporting carriages, said carriages being movable for bringing tools supported thereby into operative association with the work, a fluid operated actuating mechanism associated with each carriage, a fluid control mechanism for governing the operation of said carriage actuating mechanisms, said fluid control mechanism including a single valve unit comprising a cylindrical valve longitudinally shiftable within a valve casing, said valve being adapted for manual and hydraulic propulsion, said valve member being normally maintained hydraulically in balance in a plurality of shifted positions, said valve being provided with a plurality of oil conducting passages and said casing having a plurality of cooperative ports, means for supplying fluid to said valve unit, and fluid conducting means connecting said valve unit with the carriage actuating mechanisms.

23. A material working machine of the class described including a plurality of movable carriages, a fluid actuated operating mechanism associated with each carriage, a fluid control mechanism for governing the actuation of said carriage operating mechanisms in predetermined operating relationship, said control mechanism including a unitary valve having a plurality of fluid directing passages and a casing therefor having a plurality of fluid ports, means for supplying fluid to said control mechanism, fluid conducting means connecting said control mechanism with the carriage operating mechanisms, valve actuating mechanism for reciprocating said unitary valve within its casing, a slide movable in response to the actuation of one of said carriages, and a member adjustably mounted on said slide, adapted to engage the valve actuating mechanism, whereby to automatically control the distribution of fluid to one of said carriages.

24. A material working machine of the class described including a plurality of carriages, a fluid actuated operating mechanism associated with each carriage, a fluid control mechanism for governing the actuation of said carriage operating mechanisms in predetermined operating relationship, said fluid control mechanism including a normally balanced control valve having a plurality of fluid conducting passages, said valve being reciprocable within a casing having a plurality of cooperative fluid ports, means for supplying fluid to said fluid control mechanism, fluid conducting means connecting said control mechanism with the carriage operating mechanisms, a mechanically controlled member for causing the reciprocation of the control valve within its casing, and

means operable in response to the actuation of one of said carriages for automatically effecting longitudinal movement of the control valve.

25. A material working machine of the class described including a plurality of carriages, a fluid actuated operating mechanism associated with each carriage, a fluid control mechanism for governing the actuation of said carriage operating mechanisms in predetermined operating relationship, said control mechanism including a valve having a plurality of fluid directing passages and a casing in which said valve is reciprocable having a plurality of fluid ports, means for supplying fluid to said control mechanism, fluid conducting means connecting said control mechanism with the carriage operating mechanisms, valve actuating means including a manually operable control handle, means connecting said handle with said valve whereby said valve may be reciprocated within its casing, a reciprocable slide movable in response to the actuation of one of said carriages, and a plurality of dogs adjustably mounted on said slide, said dogs being engageable with the valve actuating means for automatically controlling the positioning of said valve within its casing.

26. A material working machine of the class described including a plurality of carriages, a fluid actuated operating mechanism associated with each carriage, a fluid control mechanism for governing the actuation of said carriage operating mechanisms, said fluid control mechanism including a unitary valve shiftable within a casing, said valve having a plurality of fluid directing passages and said casing having a plurality of co-operative fluid ports, means for supplying fluid to said control mechanism, fluid conducting means connecting said control mechanism with the carriage operating mechanisms, said valve being adapted, when occupying a predetermined shifted position, to effect the reversal of fluid flow to the carriage operating mechanisms, and means for causing said valve to be shifted to reverse position, said means including a lever mechanism, a member movable in response to the actuation of one of said carriages and adapted to operatively engage said lever mechanism upon the completion of the feeding movement of said carriage, and a member movable in response to the actuation of another of said carriages, said last named member adapted to operatively engage said lever mechanism upon the completion of the feeding movement of said last mentioned carriage, whereby the shifting of the control valve for the purpose of reversal is controlled by the tool carriage which is last to complete its feeding movement.

27. A material working machine of the class described including a carriage, a fluid actuated operating mechanism associated with said carriage, a fluid control mechanism for governing the actuation of said carriage operating mechanism, said fluid control mechanism including a unitary control valve shiftable within a casing, one portion of said valve having a plurality of fluid passages co-operative with ports in the casing to direct fluid to said carriage operating mechanism, said valve serving when in one position, to direct fluid in one direction and when in another position, to direct fluid in a reverse direction, one portion of said valve having a piston section, whereby when fluid is directed thereagainst, said valve will be shifted longitudinally within its casing, means for supplying fluid to said control mechanism, fluid conducting means connecting said control mechanism with said carriage operating mechanism, a passageway for

5 directing fluid against the piston section of said control valve, and means operable in response to the actuation of said carriage to effect the introduction of fluid within the passageway communicating with said piston section whereby to effect automatic longitudinal movement of said valve.

28. A material working machine of the class described, a movable carriage, a fluid actuated operating mechanism associated with the carriage, a fluid control mechanism for governing the actuation of said carriage operating mechanism, said control mechanism including a unitary valve longitudinally shiftable and capable of being oscillated within a casing, one portion of said valve having a plurality of fluid directing passages co-operatively arranged with respect to fluid ports in the casing, another portion of said valve having a piston section which is adapted when fluid is directed thereagainst, to cause the longitudinal shifting of said valve within the casing, a passageway for directing fluid against said piston, a passageway in said piston section for communicating with said first mentioned passageway when the valve occupies a predetermined angular relation with respect to the casing, and means for oscillating said valve to establish communication between said passageways.

29. A material working machine of the class described including a plurality of carriages, a fluid actuated operating mechanism associated with each carriage, a fluid control mechanism for governing the actuation of said carriage operating mechanisms, said control mechanism including a unitary valve shiftable within a casing, a portion of said valve having oil directing passageways co-operatively arranged with ports provided in said casing, said valve being longitudinally movable within the casing for controlling the direction of flow of fluid, said valve being capable of oscillation within its casing and provided with a piston section, a passageway adapted to direct fluid against said piston section to effect longitudinal movement of the valve, a passageway in said piston section adapted to communicate with said first mentioned passageway when the valve occupies a predetermined angular position of adjustment within its casing, and means for oscillating said valve, said means being operable in response to the actuation of one of said carriages.

30. A material working machine of the class described including a plurality of tool supporting carriages, a fluid operated actuating mechanism associated with each carriage, a main valve unit, said unit including a valve having a plurality of fluid directing passages and a casing in which said valve is reciprocable having a plurality of fluid ports, means for supplying fluid to said main valve unit, fluid conducting means connecting said main valve unit with said carriage operating mechanisms, and a control valve unit associated with said fluid conducting means for adjustably controlling the displacement of fluid therethrough whereby to adjustably control the rate of travel of said carriages.

31. A material working machine of the class described including a plurality of tool supporting carriages, a fluid actuated operating mechanism associated with each carriage, a fluid control mechanism including a main valve having a plurality of fluid directing passages and a casing in which said valve is reciprocable having a plurality of co-operative fluid ports, means for supplying fluid to said main valve, an orifice valve unit having a plurality of adjustable orifices and a

plurality of non-adjustable orifices, fluid conducting means connecting said main valve with said orifice valve, fluid conducting means connecting said orifices with said carriage operating mechanisms, and means shiftable within said orifice valve unit for controlling communication of said orifices with the fluid conducting means extending between said orifice valve unit and said main valve.

32. In a material working machine of the class described, the combination with a variable fluid displacement pump and means for controlling the degree of displacement of said pump, a plurality of carriages, operating mechanisms therefor, a main control valve unit including a valve having a plurality of fluid directing passages and a casing in which said valve is reciprocable having a plurality of co-operative fluid ports, fluid conducting means extending between said main valve unit and said variable displacement pump, said main valve serving, when in one position of longitudinal displacement within its casing, to cause the actuation of the means for controlling the displacement of said pump whereby to effect increased displacement of fluid to said main valve unit, an orifice valve unit, fluid conducting means connected between said orifice valve and said main valve, and fluid conducting means connected between said orifice valve unit and the carriage operating mechanisms, said orifice valve having adjustable and non-adjustable orifices and means for controlling the opening and closing of said orifices in accordance with the position of the valve of said main valve unit.

33. A material working machine of the class described including a rotary work support, tool carriages disposed on opposite sides of the axis of said work support and movable transversely thereof, one of said carriages being longitudinally movable with respect to the work, a fluid operated actuating mechanism for the carriages including an actuating mechanism for each carriage and a main valve unit having a plurality of fluid directing passages and a casing in which said valve is reciprocable having a plurality of fluid ports, means for supplying fluid to said main valve unit, and a orifice valve unit connected with said main valve unit, said orifice valve unit having a plurality of orifices corresponding to the number of carriage actuating mechanisms, fluid conducting means connecting said orifices with their respective carriage actuating mechanisms, said orifice valve unit having a valve for controlling the distribution of fluid to the actuating mechanism associated with the longitudinally movable tool carriage, and means for controlling the movement of said last mentioned valve in accordance with the degree of displacement experienced by one of said carriages.

34. A material working machine of the class described including a rotary work support, a tool supporting carriage which is movable transversely and longitudinally with respect to the axis of the work support, another tool carriage which is movable transversely of the work support, a fluid actuated operating mechanism associated with each carriage for effecting the movements thereof, a fluid control mechanism for governing the actuation of said carriage operating mechanisms, said control mechanism including a main control valve having a plurality of fluid directing passages and a casing in which said valve is reciprocable having a plurality of co-operative fluid ports, means for supplying fluid to said control mechanism, fluid conducting means connecting

said control mechanism with each of the carriage operating mechanisms, means for controlling the actuation of said control valve to effect the distribution of fluid to said carriage operating mechanisms, a control valve for intermittently preventing the displacement of fluid from the main control valve to one of said carriage operating mechanisms and means for controlling the operation of said last mentioned valve in accordance with the degree of displacement experienced by one of said carriages.

35. A material working machine of the class described including a rotary support, a carriage, means for driving said rotary support, a clutch mechanism for connecting and disconnecting the driving means with respect to said support, a fluid operated clutch actuating mechanism, a fluid operated actuating mechanism associated with said carriage, a fluid control mechanism for governing the actuation of said fluid operated actuating mechanisms, said control mechanism including a valve having a plurality of fluid directing passages and a casing in which said valve is reciprocable having a plurality of co-operative fluid ports, means for supplying fluid to said control mechanism, and fluid conducting means connecting said control mechanism with said carriage and clutch actuating mechanisms, said clutch actuating mechanism being operable in response to the displacement of fluid to said carriage actuating mechanism.

36. In a material working machine of the class described, a tail-stock comprising a main body, a main spindle reciprocably mounted within said body, fluid operated means for effecting reciprocation of said spindle, a center mounted in said spindle, a valve for controlling the movement of the fluid operating means, and manually operable means for actuating said valve and for locking the spindle in position.

37. In a material working machine of the class described, a tail-stock construction comprising a body portion, a main spindle reciprocably mounted within said body portion, fluid operated means for effecting reciprocation of said spindle, a center mounted in said spindle, a manually operable valve for controlling the movement of said spindle actuating means, and a ball within the spindle for taking up excess thrust load experienced by the center.

38. In a material working machine of the class described, a rotary support, a plurality of carriages movable with respect to said support, a fluid operated actuating mechanism associated with each carriage, a main control valve for controlling the supply of fluid to said mechanisms, said valve having a valve member normally balanced by fluid and longitudinally shiftable within an elongated casing, and a pocket presented in said main valve for receiving a supply of fluid to unbalance said valve member and thereby effect the shifting thereof within its casing.

39. In a material working machine of the class described, a plurality of movable carriages, a fluid displacement pump, a fluid operated actuating mechanism associated with each carriage and operatively connected with said fluid displacement pump, and a valve mechanism including a valve member longitudinally reciprocable within a casing for controlling the starting, stopping and speed of travel of said carriages, said valve member being normally maintained in balance by fluid from said pump.

40. In a material working machine, a rotary work support, a plurality of tool carriages, a

variable displacement pump, fluid operated actuating mechanisms associated with each carriage, a single automatic valve for controlling the displacement of fluid from said variable displacement pump, a distributor valve associated with said single automatic valve for controlling the displacement of fluid from said automatic valve to said carriage actuating mechanisms, a manually operable means for shifting said automatic valve, and means for controlling the displacement of said pump to effect variation in movements of said carriages.

41. In a machine tool construction, the combination of a prime mover, a rotary support, a clutch mechanism for controlling the transmission of power to said rotary support, driving means connecting said clutch mechanism with said prime mover, a fluid displacement pump, means for transmitting power from said prime mover to said pump, means for adjusting the position of the portion of said pump connected with said prime mover, and an adjustable mounting for said prime mover for adjusting the driving connection between said prime mover and said clutch mechanism.

42. In a machine of the class described, a main drive shaft, a clutch mechanism associated with said drive shaft for controlling the delivery of power thereto, a pick-off gear mounted on said shaft, a companion pick-off gear meshing with said first mentioned gear, a pinion driven by said second gear, a rotary spindle, a main gear mounted on said spindle and driven by said pinion, and means supporting said clutch mechanism, drive shaft, and pick-off gears as a unit and adapted to be detachably associated with the gear on said spindle.

43. In a material working apparatus of the class described, a rotary support, an oscillatory carriage adapted to be swung toward and away from said support, an oscillatory bar for supporting said carriage, and fluid operated mechanism for effecting longitudinal reciprocation of said oscillatory bar, said mechanism including a piston and cylinder therefor positioned axially with respect to said bar, whereby oscillation of said bar may be effected without disturbing the mechanism for longitudinally moving said bar.

44. In a material working machine of the class described, a head-stock including a rotary work supporting spindle, and a tail-stock including a work engaging centering member, said centering member being longitudinally reciprocable, fluid operated means for effecting the longitudinal movement of said centering member, and a single operating member for controlling the actuation of said fluid operated means and for contemporaneously clamping said centering member in position.

45. In a material working machine of the class described, a rotary work supporting spindle having a tapered portion at one extremity, a bearing for said tapered portion adapted to take up radial load experienced by the spindle, and an anti-friction bearing associated with the opposite extremity of said spindle for taking up thrust load experienced by the spindle, said anti-friction bearing being constantly subjected to a load greater than any axial thrust load which is normally experienced by the spindle under normal operating conditions.

46. In a material working machine of the class described, a tail-stock comprising a main body, a main spindle reciprocably mounted within said body, a tail stock center rotatably mounted with-

in the spindle, an anti-friction bearing supporting each extremity of said tail-stock center, said bearings being continuously subjected to a load which is greater than the actual working load imposed upon said center under normal operating conditions, the anti-friction bearing positioned near the forward extremity of said center being designed to take up thrust load and the other anti-friction bearing being designed to take up radial load experienced by said center.

47. In a material working machine of the class described, a rotary work supporting spindle having a tapered extremity, a tapered bearing for said spindle extremity, a mounting for said bearing, means for securing said bearing in various positions of longitudinal adjustment within said mounting, and a preloaded anti-friction bearing provided at the opposite extremity of said spindle.

48. In a material working apparatus of the class described, a rotary spindle having a tapered extremity, a tapered bearing for said spindle extremity, and a mounting for said bearing, the bearing for said spindle having a predetermined coefficient of expansion in respect to the spindle and the mounting being adapted to prevent outward expansion of the bearing due to the heat experienced during the rotation of the spindle within said bearing, whereby the bearing expands inwardly to compensate for linear expansion experienced by the spindle due to the heating thereof.

49. In a hydraulic actuator system, a plurality of hydraulic actuators, a variable displacement high pressure pumping mechanism for delivering fluid under pressure to said actuators, and a fluid distribution and orifice mechanism adapted to receive fluid delivered by said pump and provided with discharge orifices of a size corresponding with predetermined fluid pressure requirements to distribute said fluid under predetermined pressures simultaneously to the individual actuators in accordance with the pressure requirements of each actuator.

50. In a hydraulic actuator system, a plurality of hydraulic actuators, a variable displacement high pressure pump for delivering fluid to said actuators, a fluid distributing mechanism provided with discharge orifices of a size corresponding with predetermined fluid pressure requirements for controlling the distribution and orifice of fluid under predetermined pressures simultaneously to said actuators in accordance with the individual pressure requirements thereof, and a shiftable control valve interposed between said fluid distributing mechanism and said pump.

51. In a hydraulic actuator system, a hydraulic actuator including a piston shiftable within a cylinder, pumping means for supplying fluid under pressure to said actuator, a valve, said valve being shiftable to govern the rate and direction of travel of said actuator piston, and means forming a part of the valve structure to effect the unbalancing of the fluid pressure upon said valve and thereby cause the sudden shifting thereof.

52. In a hydraulic actuator system, a hydraulic actuator including a piston shiftable within a cylinder, pumping means for supplying fluid under pressure to said actuator, a valve mechanism including a valve longitudinally shiftable within a casing for controlling the delivery of fluid to said actuator, and means shiftable within the valve mechanism for effecting the unbalancing of fluid acting upon the valve to thereby cause said valve to be suddenly shifted from one position to another.

53. In a hydraulic actuator system, a hydraulic actuator including a piston shiftable within a cylinder, a pumping means for supplying pressure to said actuator, a valve mechanism interposed between said pumping means and said actuator for controlling the delivery of fluid to said actuator, said valve mechanism including an elongated valve member shiftable within a casing, and means located at one extremity of said valve for effecting the unbalancing of fluid pressure within the valve to thereby cause said valve to suddenly shift from one position to another.

54. In a hydraulic actuator system, a hydraulic actuator including a piston shiftable within a cylinder, pumping means for supplying fluid to said actuator, valve means including a casing and a valve member normally balanced by fluid pressure and longitudinally shiftable within said casing, said casing and valve member having co-operating ports for controlling the delivery of fluid to said actuator, said valve member and casing being relatively shiftable between at least five positions, and means for unbalancing the fluid pressure within said valve mechanism to effect the sudden shifting of said valve member from one position to another.

55. In a hydraulic actuator system, a plurality of hydraulic actuators, each of said actuators including a piston shiftable within a cylinder, pumping means for supplying fluid under pressure to said actuators, a valve mechanism for controlling the delivery of fluid to said actuators, said valve mechanism including a valve member shiftable within a housing and adapted in one shifted position to cause said actuators to move in a reverse direction, means for effecting the unbalancing of the fluid pressure within the valve to cause said valve member to shift and thereby condition the hydraulic actuators for reverse movement, and means for timely controlling said last mentioned means to function only when all of the actuators have completed their forward movement.

56. In material working apparatus of the class described, a rotary support, an oscillatory tool carriage for shifting a tool transversely of the support axis, hydraulic mechanism for effecting the oscillation of said tool carriage, and a pivotal support for said carriage, the axis of which is positioned beneath the rotary support axis so as to render a tool supported by the carriage visible from above during the cutting operation.

57. In material working apparatus of the class described, a rotary support, an oscillatory tool carriage for shifting a tool transversely of the support axis, hydraulic mechanism for effecting the oscillation of said tool carriage, and pivotal support for said carriage having its axis positioned sufficiently below the axis of the rotary support so as to enable transverse shifting of the tool supported by the carriage along a path which is substantially horizontal.

58. In a machine tool construction, a base, rotary supporting means mounted in said base, a prime mover, transmission mechanism interposed between said prime mover and said rotary support, said transmission mechanism including a flexible driving connection coupled with said prime mover, and an adjustable mounting for said prime mover to adjustably control the distance between said prime mover and said transmission mechanism.

59. In a material working apparatus of the class described, a tailstock comprising a main body, a center member mounted therein, said cen-

ter member being longitudinally shiftable within said body, an anti-friction bearing surrounding a portion of said center member for taking up part of an end thrust experienced thereby, and a ball positioned at the inner extremity of said center member for taking up thrust load in excess of that taken up by said anti-friction bearing.

60. In combination with a fluid transmission system including pumping means for displacing fluid, a propelling mechanism and a main fluid control valve operatively connected therewith for controlling the starting and reversing of said propelling mechanism, control mechanism operable independently of said main valve and having a fluid pressure responsive orifice for diverting a predetermined portion of the displaced fluid in response to a selectively introduced increase in resistance experienced by the propelling mechanism during the movement thereof in at least one direction without impairing the propelling power of said propelling mechanism.

61. In combination with a fluid transmission system including a pumping means for displacing fluid, a propelling mechanism and a main fluid control valve operatively connected therewith for controlling the starting and reversing of said propelling mechanism, means actuated in timed relation with the movement of the propelling mechanism for causing the shifting of said valve to reverse position, and control mechanism operable independently of said main valve including a fluid pressure responsive orifice for diverting a portion of the displaced fluid when the load is selectively varied during the movement of said propelling mechanism in at least one direction without reducing the pressure of the propelling fluid in the propelling mechanism.

62. In combination with a fluid transmission system including pumping means for displacing fluid, said pumping means being adapted to deliver fluid at various selected flow rates, a main reversing valve operatively connected with the pumping means and arranged to control the rate of fluid flow therefrom, and a fluid actuated mechanism operatively connected with said valve, fluid control mechanism including a fluid pressure responsive orifice for diverting a portion of the fluid displaced by said pumping means at a pressure experienced in said fluid actuated mechanism, and means operable in response to the actuation of said fluid actuated mechanism during the movement thereof in at least one direction for controlling the passage of fluid through said diverting orifice.

63. In combination with a fluid transmission system including pumping means for displacing fluid, said pumping means being adapted to deliver fluid at various selected flow rates, a main reversing valve mechanism operatively connected with said pumping means and arranged to control the rate of fluid flow therefrom, and a fluid actuated mechanism operatively connected with said valve, fluid control mechanism including a fluid pressure responsive orifice for diverting a portion of the fluid displaced by said pumping means without reducing the propelling effectiveness of the propelling fluid upon said fluid actuated mechanism, and valve mechanism operable in response to the actuation of said fluid actuated mechanism during the movement thereof in at least one direction for controlling the passage of fluid through said diverting orifice.

64. In combination with a fluid circuit having a high pressure pump, means for controlling the fluid displaced by said pump, said means includ-

ing a fluid pressure responsive restricted orifice through which a governed amount of fluid may be diverted from the portion of the fluid circuit connected with the discharge side of said high pressure pump without decreasing the pressure of the propelling fluid discharged by said pump, means for controlling the amount of fluid flow passing through said orifice, a hydraulic actuator including a piston within a cylinder, and valve mechanism for controlling the starting and reversal of said actuator, said fluid diverting means being adapted to function at a selected time during the movement of said actuator in at least one direction at a pressure experienced in said hydraulic actuator.

65. In a hydraulic actuator system, a shiftable supporting machine element, a hydraulic actuator for propelling said element including a piston within a cylinder, a variable displacement pump, means connecting said displacement pump with said hydraulic actuator, fluid pressure responsive diverting means interposed between said variable displacement pump and said actuator, said fluid diverting means being operable during the movement of said actuator in a given direction, whereby a predetermined amount of fluid may be diverted so as to prevent pulsative effects within the system when the actuator is subjected to an increase in load, said fluid diversion occurring without reducing the propelling effectiveness of the fluid, and means operable independently of said fluid diverting means for controlling the starting and reversal of movement of said hydraulic actuator.

66. In combination with a fluid circuit having a high pressure pump, means for controlling the fluid displaced by said pump through the circuit, said means including a fluid pressure responsive orifice through which a governed amount of fluid may be diverted from the portion of the fluid circuit connected with the discharge side of said pump without decreasing pressure of the propelling fluid displaced by said pump, means for initiating the functioning of said fluid diverting means, a hydraulic actuator, and a valve operable independently of said controlling means for governing the starting and reversal of said actuator, said fluid diverting means being adapted to function during the movement of said actuator in at least one direction at the propelling pressure experienced in said hydraulic actuator.

67. In a hydraulic actuator system, a shiftable supporting machine element, a hydraulic actuator movable in forward and reverse directions for propelling said element including a piston within a cylinder, fluid conducting means connected with said actuator, fluid diverting means including a fluid pressure responsive orifice associated with said conducting means for diverting fluid therefrom at the propelling pressure experienced in said actuator when the actuator is subjected to increase in load during the movement of said actuator in a given direction, pumping means for supplying fluid, said pumping means being adapted to deliver fluid at various selected flow rates, means for controlling the functioning of said fluid diverting means in timed relation with respect to the shifting of said machine element, and a control valve mechanism capable of being shifted to at least three positions, namely, forward, reverse, and neutral, for controlling said hydraulic actuator and for controlling the rate of fluid flow from the pumping means.

68. In a hydraulic actuator system, a shiftable

5 machine element, a hydraulic actuator movable in forward and reverse directions for propelling said element including a piston within a cylinder, fluid conducting means connected with said actuator, fluid diverting means including a fluid pressure responsive orifice associated with said conducting means for diverting fluid therefrom when the actuator is subjected to increase in load during the movement of said actuator in at least one direction, pumping means for supplying fluid, said pumping means being adapted to deliver fluid at various selected flow rates, means for controlling the functioning of said fluid diverting means in timed relation with respect to the shifting of said machine element, and a control valve mechanism capable of being shifted to at least three positions, namely, forward, reverse, and neutral, for controlling said hydraulic actuator and for controlling the rate of fluid flow from the pumping means, said control valve mechanism in its neutral position being adapted to circulate fluid in the system and thereby render the pump functionally inoperative for propelling purposes.

69. In a hydraulic actuator system, a shiftable machine element, a hydraulic actuator movable in forward and reverse directions for propelling said element including a piston within a cylinder, fluid conducting means connected with said actuator, fluid diverting means including a fluid pressure responsive orifice associated with said conducting means for diverting fluid therefrom at the propelling pressure experienced in said actuator when the actuator is subjected to increase in load during the movement of said actuator in at least one direction without impairing the propelling effectiveness of the propelling fluid in said actuator, pumping means for supplying fluid, said pumping means being adapted to deliver fluid at various selected flow rates, means adapted to be automatically engaged by the structure of said shiftable machine element for controlling the operative functioning of said fluid diverting means, and valve means for controlling the direction of movement of said hydraulic actuator and for controlling the rate of fluid flow from the pumping means.

70. In a hydraulic actuator system, a shiftable machine element, a hydraulic actuator movable in forward and reverse directions for propelling said element and including a piston within a cylinder, fluid conducting means connected with said actuator, fluid diverting means including a fluid pressure responsive orifice associated with said conducting means for diverting fluid therefrom at the propelling pressure of the propelling fluid in said actuator when the actuator is subjected to increase in load during the movement of said actuator in at least one direction, pumping means for supplying fluid, said pumping means being arranged and constructed to deliver propelling fluid at various selected rates of flow, means actuated by fluid pressure for controlling the effective propelling fluid flow from the pumping means, means for controlling the functioning of said fluid diverting means in timed relation with respect to the shifting of said machine element, and a control valve mechanism capable of being shifted to at least three positions, namely, forward, reverse, and neutral, for controlling said hydraulic actuator, and for controlling said pressure actuated pump flow control means.

71. In combination with a hydraulic actuator for propelling machine parts and the like which includes a cylinder and piston construction,

pumping means having a relatively large volume rapid traverse delivery rate and a relatively low volume feeding delivery rate for delivering fluid for propelling purposes to said actuator, and a fluid control means including a restricted orifice for receiving fluid discharged from said actuator during the feeding movement thereof in a given direction, means for rendering said restricted orifice functionally ineffective when the actuator is moving at a faster rate in the same direction, control valve means for directing fluid to either end of said actuator, and for varying the delivery rate of said pumping means, and a relief valve associated with the outlet side of the pumping means for relieving the fluid therefrom when the pumping pressure exceeds a predetermined amount.

72. In combination with a hydraulic actuator for propelling machine parts and the like which includes a cylinder and piston construction, variable displacement pumping means for delivering fluid under pressure for propelling purposes to said actuator, fluid pressure responsive means for controlling the displacement of the pumping means, and a fluid control means including a restricted orifice for receiving fluid discharged from said actuator when said actuator moves at a feeding rate, a less restricted orifice for receiving fluid discharged from said actuator when said actuator moves at a faster rate, and means operable in timed relation with the movement of said actuator for controlling the operative function of said orifices, and for controlling the functioning of said pressure responsive pump displacement varying means.

73. In combination with a hydraulic actuator for propelling machine parts and the like which includes a cylinder and piston construction, pumping means for delivering fluid under pressure for propelling purposes to said actuator, a control valve for controlling the fluid flow from the pumping means to the actuator, and a fluid control means including a fluid passageway having an adjustable restricted orifice for receiving fluid discharged from said actuator when said actuator moves at a feeding rate, means for maintaining said passageway full of fluid on the discharge side of said restricted orifice during the operative functioning of said pumping means, a less restricted orifice for receiving fluid discharged from said actuator when said actuator moves at a faster rate, and means for controlling the operative functioning of said orifices.

74. In a material working machine of the class described, a rotary work support, hydraulically actuated mechanism for starting and stopping the movement of said work support, an oscillatory tool carriage for shifting a tool transversely of the support axis, a bar parallel with said support axis and providing a support for the carriage, hydraulic mechanism including a cylinder and piston structure for controlling the oscillation of said carriage, and control means for controlling the timed relation of operation of said hydraulic mechanisms.

75. In a material working machine of the class described, a rotary work support, hydraulically actuated mechanism for starting and stopping the movement of said work support, a tool carriage capable of oscillation transversely of the work support and reciprocable longitudinally thereof, a bar extending in parallelism with the support axis and providing a support for the carriage, and fluid power means for controlling

the oscillation of said carriage and for reciprocating said carriage, and control means for controlling the timed relation of operation of said hydraulic mechanism and said fluid power means.

76. In a material working machine of the class described, a rotary work support, hydraulically actuated mechanism for starting and stopping the movement of said work support, an oscillatory tool carriage, a bar extending in parallelism with the support axis and providing a support for the carriage, hydraulic mechanism including a cylinder and piston construction for controlling the oscillation of said carriage, and means operable in timed relation with the movement of said tool carriage for controlling the period of actuation of said hydraulic mechanisms.

77. In a machine tool, tool supporting means, work supporting means, said work and tool supporting means being capable of relative movement with respect to each other, hydraulic means including pumping means for feeding one of said means toward the other, and means for regulating the rate of feed of one of said tool and work supporting means including a closed chamber, a fluid passageway, a restricted outlet in said passageway communicating with said closed chamber, the regulation of the feed being regulated by the rate of flow of a fluid from said closed chamber through said restricted outlet, and means for maintaining said passageway full of fluid on the discharge side of said restricted outlet during the operative functioning of said pumping means.

78. In a machine tool, a rotary spindle, an electric motor for rotating said spindle, a support, said spindle and support being adapted to operatively support a cutting tool and a workpiece, a first reciprocable hydraulic actuator for causing relative movement between the spindle and the support axially of the spindle whereby to cause the tool to engage and machine the workpiece, pumping means for propelling said first actuator at feeding and rapid traverse rates, shiftable valve mechanism and hydraulic circuits including a restricted orifice means for controlling the movements and speed of travel of the first hydraulic actuator, means for starting and stopping the rotation of the spindle in timed relation with the movements of said first actuator, and a second hydraulic actuator operable in timed relation with the movements of said first actuator for causing relative transverse movement between the spindle and support to cause the tool to clear the work.

79. In a machine tool, a rotary spindle, an electric motor for rotating said spindle, a support, said spindle and support being adapted to operatively support a cutting tool and a workpiece, a first reciprocable hydraulic actuator movable forwardly through a feeding travel and rearwardly for causing relative reciprocable movement between the spindle and the support axially of the spindle whereby to cause the tool to engage and machine the workpiece, pumping means for propelling said first actuator at feeding and rapid traverse rates, shiftable valve mechanism and hydraulic circuits including a restricted orifice means for controlling the movements and speed of travel of the first hydraulic actuator, means for stopping the rotation of the spindle when said first actuator reaches the end of its feeding travel, and a second hydraulic actuator operable when said first actuator reaches the end of its feeding travel for causing relative

transverse movement between the spindle and support to cause the tool to clear the work on the rearward movement of said first hydraulic actuator.

80. In a machine tool, a rotary spindle, an electric motor for rotating said spindle, a support, said spindle and support being adapted to operatively support a cutting tool and a workpiece, a first reciprocable hydraulic actuator for causing relative movement between the spindle and the support axially of the spindle whereby to cause the tool to engage and machine the workpiece, pumping means for delivering a relatively large volume of fluid for propelling said first actuator at a rapid traverse rate and for delivering a relatively small volume of fluid for propelling said first actuator at a feeding rate, shiftable valve mechanism and hydraulic circuits including a restricted orifice means for controlling the first hydraulic actuator during its feeding travel, means for starting and stopping the rotation of the spindle in timed relation with the movements of said first actuator, and a second hydraulic actuator operable in timed relation with the movements of said first actuator for causing relative transverse movement between the spindle and support to cause the tool to clear the work.

81. In a machine tool the combination of a tool holding member adapted to carry a tool, a work holding member adapted to carry a workpiece, an electric motor for imparting relative

5 rotative movement between said members, a first cylinder and piston structure operatively associated with one of said members for imparting a relative shifting between said members along a given axis of travel for feeding and rapid traverse movements, power driven pump means for propelling said first cylinder and piston structure at feeding and rapid traverse rates, shiftable valve means and hydraulic circuits including a restricted orifice means for controlling said relative rapid traverse and feeding movements between said tool and work holding members, a second cylinder and piston structure for imparting a relative positioning between the work holding member and the tool holding member in a direction transverse to said first named axis of travel, whereby to arrange said members for a metal removing process by the tool upon the workpiece by relative movement of said members in one direction along said first named axis and for clearance between the tool and workpiece upon movement of said members in the opposite direction, a second valve means for controlling the operative movements of the second cylinder 10 and piston structure in timed relation to the movements of the first cylinder and piston structure, and means for starting and stopping the rotative movement between said members in timed relation to the movements of said first cylinder and piston structure.

ERNEST J. SVENSON.

CERTIFICATE OF CORRECTION.

Patent No. 2,372,692.

April 3, 1945.

ERNEST J. SVENSON.

It is hereby certified that error appears in the printed specification of the above numbered patent requiring correction as follows: Page 2, first column, line 67, for "adanveed" read --advanced--; and second column, line 41, for "disclosed" read --disclose--; page 3, second column, line 51, for "extremely" read --extremity--; page 4, first column, line 37, for "acuation" read --actuation--; line 63, for "ail" read --oil--; page 5, first column, line 56, for "bar 162" read --bar 262--; and second column, line 17, for "on" before "orifice" read --or--; line 45, for "Fig. 20" read --Fig. 22--; page 16, second column, line 50, claim 50, after "distribution" strike out "and orifice"; and insert the same in line 47, same claim, after "distributing"; and that the said Letters Patent should be read with this correction therein that the same may conform to the record of the case in the Patent Office.

Signed and sealed this 18th day of December, A. D. 1945.

transverse movement between the spindle and support to cause the tool to clear the work on the rearward movement of said first hydraulic actuator.

80. In a machine tool, a rotary spindle, an electric motor for rotating said spindle, a support, said spindle and support being adapted to operatively support a cutting tool and a workpiece, a first reciprocable hydraulic actuator for causing relative movement between the spindle and the support axially of the spindle whereby to cause the tool to engage and machine the workpiece, pumping means for delivering a relatively large volume of fluid for propelling said first actuator at a rapid traverse rate and for delivering a relatively small volume of fluid for propelling said first actuator at a feeding rate, shiftable valve mechanism and hydraulic circuits including a restricted orifice means for controlling the first hydraulic actuator during its feeding travel, means for starting and stopping the rotation of the spindle in timed relation with the movements of said first actuator, and a second hydraulic actuator operable in timed relation with the movements of said first actuator for causing relative transverse movement between the spindle and support to cause the tool to clear the work.

81. In a machine tool the combination of a tool holding member adapted to carry a tool, a work holding member adapted to carry a workpiece, an electric motor for imparting relative

5 rotative movement between said members, a first cylinder and piston structure operatively associated with one of said members for imparting a relative shifting between said members along a given axis of travel for feeding and rapid traverse movements, power driven pump means for propelling said first cylinder and piston structure at feeding and rapid traverse rates, shiftable valve means and hydraulic circuits including a restricted orifice means for controlling said relative rapid traverse and feeding movements between said tool and work holding members, a second cylinder and piston structure for imparting a relative positioning between the work holding member and the tool holding member in a direction transverse to said first named axis of travel, whereby to arrange said members for a metal removing process by the tool upon the workpiece by relative movement of said members in one direction along said first named axis and for clearance between the tool and workpiece upon movement of said members in the opposite direction, a second valve means for controlling the operative movements of the second cylinder 10 and piston structure in timed relation to the movements of the first cylinder and piston structure, and means for starting and stopping the rotative movement between said members in timed relation to the movements of said first cylinder and piston structure.
